UNITED STATES PATENT OFFICE

160,138

PISTOL GRIP SPOTLIGHT OR THE LIKE

Clifford G. Barrett, Newark, N. J., assignor to The Portable Light Company, Inc., New York, N. Y., a corporation of New York

Application January 20, 1950, Serial No. 7,360

Term of patent 7 years

(Cl. D48—20)

To all whom it may concern:

Be it known that I, Clifford G. Barrett, a citizen of the United States of America and a resident of Newark, county of Essex, and State of New Jersey, have invented the new, original, and ornamental Design for a Pistol Grip Spotlight or the like, of which the following is a specification, reference being had to the accompanying drawing, forming part hereof, in which—

Fig. 1 is a side elevational view of a pistol grip spotlight, showing my new design;

Fig. 2 is a front elevational view thereof;

Fig. 3 is a top plan view;

Fig. 4 is a rear elevational view; and

Fig. 5 is an exploded side elevational view partly in section.

I claim:

The ornamental design for a pistol grip spotlight or the like, as shown.

CLIFFORD G. BARRETT.
